UNITED STATES PATENT OFFICE.

CHARLES C. BADEAU, OF WINTHROP, MASSACHUSETTS, ASSIGNOR TO SEARS B. CONDIT,
JR., OF BROOKLINE, MASSACHUSETTS.

HIGH-POTENTIAL ELECTRIC SWITCH.

1,054,893.

Specification of Letters Patent.

Patented Mar. 4, 1913.

Application filed February 24, 1911. Serial No. 610,593.

To all whom it may concern:

Be it known that I, CHARLES C. BADEAU, a citizen of the United States, residing at Winthrop, in the county of Suffolk and State 5 of Massachusetts, have invented certain new and useful Improvements in High-Potential Electric Switches, of which the following is a full, clear, and exact specification.

This invention relates to high potential 10 electric switches, the object being to provide a switch of this kind which will withstand very high voltages and which will embody means for reducing the potential to a lower value so that it may be led away from the 15 switch at a voltage safe to handle on a switchboard or translating devices.

With voltages of thirty thousand and upward, it is necessary to exercise extraordinary care in the insulation to prevent surface 20 leakage and striking of an arc. This is ordinarily effected by employing porcelain insulators and separating them a wide distance and so constructing them that a long path between live parts and the supporting 25 mechanism is provided, and by making and breaking the circuit under oil. Such a construction, however, only partially solves the problem of high potential transmission, since the leads which carry the energy from the 30 switch are also at a high potential and require extraordinary care and much space in safely protecting them against grounding or cross-connection. I so construct the switch that it may be of a comparatively 35 small size, the high potential leads being carried in the usual manner in porcelain insulators, but I mount the insulators at an angle so as to give a longer air path to the uninclosed live parts, and I provide also 40 within the oil bath a transformer by which the potential may be reduced and the current of a relatively lower and safe voltage may be led for distribution away from the high potential apparatus as for example to 45 measuring instruments and trip coils on a switchboard. For the purpose of reducing the voltage, I prefer to employ a series transformer which I preferably mount upon the movable element of the switch, so that when 50 the switch is open the transformer is disconnected from the circuit, but simultaneously with the closure of the switch and the transmission of high potential currents the series transformer is brought into commis- 55 sion and its secondary delivers at fixed ter-

minals a voltage safe to handle. The high voltage energy is brought to line terminals mounted on porcelain insulators a safe distance from the working mechanism and connected with insulated switch leads by disconnecting switches which establish or dis-establish a working relation with the high potential source of supply. 60

My invention therefore consists of a high potential switch provided with circuit making and breaking apparatus in an oil bath, and a transformer in the same bath adapted to be thrown into and out of circuit when the switch is operated. 65

It comprises further a structure of this kind in which the transformer is made a part of the movable switch element, the primary terminals of the transformer being in co-operative relation to the fixed line terminals of the switch. It comprises also an organization of this kind in which the secondary of the transformer is led from the switch to fixed terminals for taking off a relatively low voltage current. 75

It comprises also an oil switch in which the high potential leads are mounted in multi-section porcelain insulators supported at an angle to give increased striking distance at the outer ends, and disconnecting switches adapted to make and break connections with the line terminals. 80

Other features of novelty will be more particularly hereinafter described and defined in the claims. 85

In the accompanying drawings to illustrate the invention, Figure 1 is a side elevation partly in section of a high potential switch embodying my improvements; Fig. 2 is a similar view at right angles of the plane of that of Fig. 1; Fig. 3 is a top plan view on a reduced scale of the switch shown in Figs. 1 and 2; Fig. 4 is a diagrammatic view showing details of the series transformer and its circuits, and Fig. 5 shows a form of the switch without a series transformer. 90

Referring first to Figs. 1 to 4, 1, 2, 3, 4 represent tubular iron or steel supports upon which is mounted a casting 5, which forms a supporting structure for the switch parts, casting 5 constituting a cover for an oil vessel or tank 6 resting on adjustable brackets 7, 7^a. The oil tank may be constructed of galvanized sheet iron reinforced by strengthening bands, as indicated, and 105 110

lined with fiber or similar insulating material. The top of the casting is provided with flanged openings 6^a, 6^b, the axes of which incline outwardly, the openings forming seats for porcelain insulators 47^a, 47^b. I preferably employ a group of similar insulators, which are tapered hollow structures adapted to nest or telescope into one another, the joints being firmly bonded by an insulating cement. Within each group of insulators is a copper rod 8 (see Fig. 5) having a flange at one end and a nut at the other. These rods are shorter than the aggregate length of the multiple insulator and are spaced within the insulator by wooden blocks 9, 9^a, the parts being adjusted into tight fitting relation by means of copper plates at the ends. One of these plates forms a connecting clip for the disconnecting switch, and the other the switch terminal lying below the oil line in the tank. Disconnecting switches 10, 10^a are pivoted on a bracket forming part of the upper plates of each terminal and a stop 12 (see Fig. 5) is mounted on the plate to limit the swinging movement of the disconnecting switch when it is operated to disconnect the line. The upper ends of the disconnecting switches engage terminals 13, 13^a supported on the ends of a long porcelain insulator 15 (see Fig. 1), the central point of the insulator 15 is provided with a neck inclosed in a wooden board 16 mounted on the upper ends of iron tubes 17, 18, secured on the casting 5. These tubes form guides for a cross-head 19 mounted in sliding relation thereto. The cross-head is provided with metallic guides 19, 19^a pivotally connected with the toggle links 20 on one of which is pivoted a bell-crank connected with the operating mechanism leading away from the switch, as indicated at 21. From the crosshead depends a wooden board 22, on the lower end of which is supported in the oil tank a laminated bridging contact. This may be a simple bridging contact as indicated in Fig. 5, mounted on a block secured in the board, or, in the case of very high voltages it may be a series transformer, the primary terminals of which 27, 28 form two bridging contacts. Thus when the operating mechanism is actuated the toggles are straightened or buckled and the movable switch element raised or lowered into the oil bath. The secondary circuit of the transformer is carried away from the oil, being mounted on the wooden board and leading out of the tank through a wide opening which may contain an insulator 23 upward to the cross-head. This structure will be more readily understood by an examination of Figs. 2 and 4, the secondary terminals being indicated at 29 and 30 supported on the wooden board and connected at the top with light springs 31, 31^a extending horizontally and

making a sliding contact with vertical rails 32, 33, supported on the casting forming the top of the switch. From these rails the external secondary circuit leads through fixed clips 34, 35 with which the spring blades 31, 31^a make good electrical connection when the circuit is closed; that is to say when the movable contact is shifted upwardly into engagement with the fixed contacts 27, 28. The open position of the movable bridging contact is indicated in dotted lines Figs. 1 and 5, the guides being indicated at 19^a.
70

The series transformer is formed of a bundle of iron punchings 36, thoroughly insulated and having the primary and secondary windings on opposite sides of the rectangular opening. It is then inclosed within a tubular envelop and filled with insulating compound and clamped between bifurcated ends of the wooden board 22, as will be clearly understood from an inspection of Figs. 1, 2 and 4.
75

In Fig. 5, I have omitted the transformer as my improvements may in some cases be used without it. In this structure the bridging contact 26 is mounted on a wooden block 37 bolted in the board 22 in a manner similar to the mounting of the transformer. When the switch requires attention so that an operator must approach and handle it, the switch is first operated so that the contacts are broken in the oil, and the line potential is then cut off from any part of the switch by the operator pulling open the disconnecting switches 10, 10^a by means of a long wooden rod so as to permit him to render any part of the switch absolutely dead before handling it.
90

Having thus described my invention I declare that what I claim as new and desire to secure by Letters Patent is,—
95

1. A high potential switch having an oil tank in which the circuit is made and broken, a series transformer within the tank having its primary leads connected to and movable with the movable switch element.
100

2. A high potential switch having an oil tank in which its circuit is made and broken, a series transformer beneath the oil level connected to the movable switch element, the primary leads of the transformer being adapted to bridge the fixed contacts of the switch.
115

3. A high potential switch having an oil tank in which the circuit is made and broken, a series transformer beneath the oil movable with the switch element having its primary terminals made and broken coördinately with the closure of the switch circuit, and secondary transformer leads extending to fixed contacts outside of the oil tank.
120

4. A high potential oil switch having an oil immersed series transformer, means for coördinately closing the primary circuit of 130

- the transformer and the switch, and secondary transformer terminals extending out of the switch in sliding relation to fixed contacts leading to an external circuit.
5. A high potential oil switch comprising insulators in the oil tank extending beneath the oil level, disconnecting switches pivoted on the insulators outside the tank, a line insulator and line terminals therefor supported by the switch frame, said disconnecting switches adapted to make and break connection with the line terminals to isolate the switch.
6. In a high potential oil switch a multi-part insulator with a stud extending through the same, one end of the stud serving as a contact plate beneath the oil and the other end as the fixed terminal of a disconnecting switch, a disconnecting switch, a line insulator supported from the switch frame and a line terminal on the insulator cooperating with the disconnecting switch.
7. An electrical switch comprising an oil tank insulators extending beneath the level of the oil, said insulators being formed of a multiplicity of similar parts meshing one into the other to form double walled insulation against grounding and mounted to incline outwardly from the operating mechanism.
8. In a high potential switch the combination of main fixed and movable contacts, line terminals, and disconnecting switches for making connection of the main contacts with the line terminals, the support for the line terminals serving as a guide to direct the movement of the movable contact in a rectilinear path.
9. In a high potential oil switch fixed and movable contacts with an insulating carrier for the movable contact operating on a guide frame, the insulating carrier consisting of a mechanically strong member of semi-flexible or elastic material extending into the oil and clamping a highly insulating support for the moving contact, the mechanically strong member of semi-flexible or elastic material serving as a barrier between the opposite fixed contacts.
10. A high potential switch provided with a movable bridging contact, fixed contacts in an oil bath, and a wide movable barrier of insulating material carrying the movable contact, and extending out of the oil bath.
11. A high potential switch provided with a movable bridging contact, fixed contacts, housed in insulators dipping in oil and inclining away from each other outwardly in the air, and a wide movable insulating barrier between the fixed contacts carrying the movable contact, said barrier extending through the switch cover.
12. A high potential switch comprising an oil bath, sectional insulators having their sections tapering and nested within the insulators, said insulators having their lower ends immersed in the oil bath and being supported at an angle to one another to increase the striking distance.
- In testimony whereof I affix my signature, in presence of two witnesses.
